UNITED STATES PATENT OFFICE.

EDWARD B. HOUGH, OF PROVIDENCE, RHODE ISLAND.

MATCH BOX.

Application filed March 9, 1927. Serial No. 173,830.

The invention relates to match boxes of the type usually carried around in the pocket and used to hold a package of matches having a striking surface, and, 5 more particularly, to a construction of a match box of this type having a fire wall between the matches and the striking surface so that in striking a match the travel of fire from the striking surface to the 10 matches will be positively prevented.

According to the invention a match box is provided which may comprise a pair of covers in one or both of which may be disposed a package or book of matches of the 15 usual construction. In a match box in which a match book is provided in each cover, each cover may be provided with a fire wall between the matches and the striking surface, which walls may overlap when the covers 20 are in approximately closed position. The fire walls may also serve as retaining means for holding the books in the covers. In order to light a match it may be placed with its head between the striking surfaces of 25 the match box and the match given a quick pull out of the box. The fire wall positively prevents any travel of fire or sparks from the striking surfaces to the matches in the box.

30 The invention also consists in certain new and original features of construction and combinations of parts hereinafter set forth and claimed.

Various other features and advantages of 35 the invention will be apparent from the following particular description and from an inspection of the accompanying drawings.

In the drawings:—

40 Fig. 1 represents a longitudinal section through the match box, the covers being shown in open position, one cover being shown as having a book of matches therein and the other cover being shown empty for 45 purpose of clearly showing the construction of the cover.

Fig. 2 represents a plan view of one of the covers, the match box being in open position.

50 Fig. 3 is a detailed section through the hinge.

Fig. 4 is a perspective showing a match being disposed between the striking surfaces in position to be pulled out of the box to 55 light the match.

In the following description and in the claims parts will be identified by specific names for convenience, but they are intended to be as generic in their application to similar parts as the art will permit.

Like reference characters denote like parts in the several figures of the drawings.

Referring to the drawing a match box is shown, for the purpose of illustration, arranged to have a match book in each cover. It will be understood, however, that the invention is equally applicable to a match box arranged to have a match book in one of the covers only.

The match box may comprise a pair of 70 covers 1 and 2, the base cover 1 comprising a bottom wall 3, a front wall 4, a back wall 5 and side walls 6. The shape is generally rectangular with the front and back walls rounding into the bottom wall. The cover is made slightly deeper at the back end, the depth decreasing uniformly toward the 75 front end. Each side wall 6 may have a notch 13 which is disposed at the end of the striking strip 27 of the match book 23 for a purpose hereinafter shown.

The base cover 1 is provided with a transverse member 7 extending between the side walls generally in the shape of an angle iron. The horizontal flange 8 of the transverse member 7 has reduced extensions which fit in holes 9 in the sides 6 of the cover. Tongues are punched out of the horizontal flange 8 and bent upwardly and away from the hinge to form hooks 10 for a purpose 80 herein described more in detail. The transverse member 7 has a vertical flange 11 extending upwardly to act as a fire wall.

The top cover 2 is made substantially the same as the top cover 1 and has a fire wall 12 which overlaps the fire wall 11 when the box is closed or in the position for striking a match as shown in Fig. 4.

The covers are hingedly connected together at their back walls by a hinge construction having a spring built therein to continually urge the covers into closed relation. This hinge, a detail of which is shown in Fig. 3, may be made up of interfitting knuckles secured to the covers, alternate knuckles 17 and 18 of one cover interfitting alternate knuckles 19 and 20 on the other. A hollow pintle 14 may be provided having a coil spring 15 disposed therein, the ends 16 of the spring, being bent to engage 100 105 110

notches in the end hinge knuckles 17 and 20 so that the spring will continually urge the covers into closed position.

It is obvious that this match box may be used with different forms of match books or match packages. For purposes of illustrating the invention a single form of match book will be described. This match book 23 is of a type commonly used and comprises a plurality of sheets of paper board partially cut to form matches 25, the sheets being fastened between the back cover 26 of the match book and the striking member 27 by a fastener 24. The striking strip or member 27 is provided with striking material to provide a striking surface for igniting the matches in the well known manner.

In order to place the book 23 of matches in a cover the book has its back cover 26 torn so that the book of matches appears as shown in Figs. 1 and 2. To insert the book of matches in a cover, the book is placed with its striking member 27 under the transverse member 7 between the transverse member and the hinge, and the book pushed under the transverse member to the position shown in Figs. 1 and 2, the striking member 27 being disposed in the hooks 10. It will be understood that a match book is placed in the top cover 2 in the same manner.

When it is desired to ignite a match, the match box may be opened and a match 25 broken off from the book in the usual manner. The match is then placed in the position shown in Fig. 4 with its head between the striking members 27 of the match books with the end of the match protruding through the notches 13. The match is then pulled out with a jerk, the scraping of the match head on the striking surfaces insuring quick and certain ignition of the match.

This construction insures that the matches are easily lighted without the liability of breaking the cardboard shank of the match. Igniting the remaining matches is positively prevented by the firewalls since, when the match box is in the nearly closed position shown in Fig. 4 with the fire walls overlapping, it is impossible for sparks to fly or the wind to blow the flame from the ignited match to cause the remaining matches to ignite. Furthermore, the construction is such that the case may be inexpensively made and yet it will stand up in use and give faithful service. There are no parts to break or get out of order, and the match box is simple to operate and the matches may be ignited with great certainty and safety.

While certain novel features of the invention have been shown and described and have been pointed out in the annexed claims, it will be understood that various omissions, substitutions and changes in the forms and

details of the device illustrated and in its operation may be made by those skilled in the art without departing from the spirit of the invention.

What is claimed is:

1. A match box comprising covers members each having a bottom wall and side and end walls, hinge means connecting said cover members at the back end walls thereof, each cover member having a fire wall extending between and fixedly secured to its side walls and adapted to hold a package of matches in said cover member, a side wall of each cover member having a notch disposed at the end of the striking surfaces of said package, whereby a match may be held with its head between the striking surfaces of said books and pulled out to light said match. 70 75 80

2. A match box comprising cover members each being adapted to hold a plurality of matches and a striking surface, each cover member having a fire wall between the heads of said matches and said striking surface, said walls overlapping when said cover members are in substantially closed position. 85 90

3. A match box comprising a body member having a rectangular bottom, front and back walls and side walls, a cover hingedly connected to said back wall and engaging said front wall, a side wall having a notch in the top near the front wall, said body having a first fire wall extending between said side walls for holding a book of matches having a striking surface extending away from said notch, said fire wall being disposed between said striking strip and the heads of the matches in said book, and a second fire wall secured to said cover and overlapping said first fire wall when the box is closed. 100 105 110

4. A match box comprising a body member having side walls, provided with openings, a cover separably connected to said body member, a transverse member disposed in said openings, said transverse member having a retaining portion provided with hooks, and an upstanding portion providing a fire wall, said body being adapted to have a bundle of matches having a striking strip held under said retaining portion with the striking strip under said hooks and the fire wall between said striking strip and the heads of the matches. 115

5. In combination, a match box comprising a body member, a plurality of matches and a striking surface disposed in said body member, a cover member, there being a sliding surface disposed in said cover member, a first fire wall secured to said body member between said striking surface and the heads of said matches, said cover member being unitary and adapted to substantially close the box, a second fire wall secured to said cover member and overlapping said 120 125 130

first fire wall when the box is closed, and hinge means connecting an edge of said cover member to an edge of said body member, whereby a match may be struck by placing the head between said striking surface and sliding surface and then pulling said match.

6. In combination, a match box comprising a body member, a plurality of matches and a striking surface disposed in said body member, a cover member, there being a sliding surface disposed in said cover member, said cover member being unitary and adapted to substantially close said box,

hinge means connecting an edge of said cover member to an edge of said body member, safety fire preventing devices providing an effective and complete barrier between said surfaces and the heads of said matches when a match is placed with its head between said surfaces to be pulled out of the box to light the match, said devices allowing at the same time closing of said box.

In testimony whereof I have hereunto set my hand.

EDWARD B. HOUGH.
